UNITED STATES PATENT OFFICE.

ALOYSIUS C. LIPPERT, OF KENOSHA, WISCONSIN, ASSIGNOR OF ONE-HALF TO C. A. NORTON, OF CHICAGO, ILLINOIS.

DESIGN FOR AN AUTOMOBILE RADIATOR CAP.

Application filed October 17, 1924. Serial No. 11,091. Term of patent 3½ years.

To all whom it may concern:

Be it known that I, ALOYSIUS C. LIPPERT, a citizen of the United States, residing at Kenosha, in the county of Kenosha and State of Wisconsin, have invented a new, original, and ornamental Design for Automobile Radiator Cap, of which the following is a specification, reference being had to the accompanying drawing, forming a part thereof.

On the drawing,

Figure 1 is a top plan view of a radiator cap embodying my new design; and

Fig. 2 is a front elevation thereof, showing in dotted lines a temperature indicator as an example of devices which may be carried by the cover of the radiator cap, a portion of the radiator and filler neck being also shown in dotted lines.

I claim:

The ornamental design for an automobile radiator cap as shown.

ALOYSIUS C. LIPPERT.
